(57) **CLAIM**

The ornamental design for an emergency assistance device for a firearm, as shown and described.

DESCRIPTION

FIG. 1 is a front perspective view of the emergency assistance device for a firearm;

FIG. 2 is a left elevation view thereof;

FIG. 3 is a right elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a front perspective view of the emergency assistance device according to an alternative embodiment;

FIG. 9 is a left elevation view of the emergency assistance device of FIG. 8;

FIG. 10 is a right elevation view of the emergency assistance device of FIG. 8;

FIG. 11 is a front elevation view of the emergency assistance device of FIG. 8;

FIG. 12 is a rear elevation view of the emergency assistance device of FIG. 8;

FIG. 13 is a top plan view of the emergency assistance device of FIG. 8; and,

FIG. 14 is a bottom plan view of the emergency assistance device of FIG. 8.

The broken lines illustrate environment and are included for the purpose of identifying unclaimed features of the design.

1 Claim, 8 Drawing Sheets
